UNITED STATES PATENT OFFICE

JAMES R. JORDAN, OF SOUTH BEND, INDIANA

CONDUIT TRACTOR

Application filed May 31, 1929. Serial No. 367,597.

This invention relates to an improved automatically operable and self acting tractor expressly intended to pull lead wires through underground conduits, pipes, and the like.

It is a matter of common knowledge that considerable trouble is encountered, and many handicaps faced in pulling cables through conduits. Organizations who lay and maintain underground cables face the problem of getting the lead wires through the ducts. This lead wire, as is well known is a light weight wire used to pull a steel cable through. The steel cable is used to pull the electric cable.

Under ordinary conditions the common method of getting the lead wire through is to use four foot wooden rods which have a hook on one end and an eye on the other end. One rod or stick is pushed into the duct and another hooked onto it and pushed forward and so on until the next man hole is reached by the first rod, then the lead wire is fastened on to the last rod and the rods are pulled through and disconnected in the second man hole. By this method a rodding gang of approximately eight men can pull about four thousand feet of wire in an eight hour day.

Being familiar with the difficulties experienced and expense attached to this method of rodding and wire pulling, I have conceived and evolved and produced what I believe to be a modernized and practicable machine for doing this work. The machine is in the form of a tractor whose configuration is such as to permit it to be placed in the conduit, and it includes an electric motor, which when started causes the machine to literally crawl through and to pull the wires attached thereto.

Stated otherwise I have developed what I believe to be an unusual contribution to this art which is comparatively compact, convenient, economical and otherwise well fitted for fulfilling the requirement of a tractor or machine of this class.

The particular structural details and relative arrangement and association of the parts will become more readily apparent from the following description and drawings.

In the drawings:

Figure 1 is a side elevational view of the complete tractor as constructed in accordance with the present invention.

Figure 2 is a transverse vertical section on the line 2—2 of Figure 1.

Figure 3 is a transverse vertical section on the line 3—3 of Figure 4.

Figure 4 is a central vertical longitudinal section through the rear half of the device.

Figure 5 is a view in section and elevation of the forward half.

Figures 6 and 7 are transverse vertical sections taken approximately on the plane of the line 6—6 and line 7—7, respectively, of Figure 1.

Figure 8 is a top plan view of a resilient roller bracket.

Figure 9 is a view of a slightly modified embodiment of the invention.

A general understanding of the invention may be had by referring especially to Figures 1, 4, and 5. The tractor is composed of a plurality of sections of general cylindrical cross section in configuration, whereby to permit it to be placed in an ordinary electric conduit and to crawl therethrough unhampered. At the forward end I provide a thrust nose in the form of a substantially cylindrical cap 10 constructed to accommodate an anti-friction roller 11. The peripheral portion of the roller is exposed in order to permit it to rest in rolling contact with the internal surface of the conduit (not shown). This so called thrust nose is to be of a diameter slightly less than the conduit and is intended to engage any objects that may be in the conduit and to force them out to prevent unimpeded travel of the tractor through the conduit. This nose forming cap is fastened to the forward end of a tubular motor housing 12 as seen particularly in Figure 5. An appropriate electric motor of substantially one-half horse power is arranged in this housing. The shaft 13 and the motor passes through a closing disc 14 where it is coupled as at 15 with the driven shaft 16, the driven shaft is mounted for rotation in an intermediate part or section of the device. This part is made to provide bearings for rotatable mounting of the driven shaft 16. Then at

90

95

100

one end it is formed to accommodate the power transmission means, for instance there is a beveled pinion 17 mounted on the shaft 16 and in mesh with a beveled gear 18 on the 5 transverse horizontal shaft 19. This shaft as shown in Figure 3 is mounted in appropriate bearings in the cast base 20 of this intermediate section. This base is of the approximate configuration shown in Figure 10 3 to permit it to ride through the conduit. The shaft 19 is provided with a sprocket wheel 21 and a chain 22 is trained over this and is connected with a complementary sprocket 23 on a spaced parallel power take. 15 off shaft 24. This intermediate part of the structure includes an appropriate shaped shell made up of sections 25 and 26 as shown in Figure 3. Current can be supplied to the motor in any suitable manner.

20 The remainder or rear end portion of the device comprises suitably shaped body 27 having a depending rib 28 fashioned to provide a bearing for the rear idling shaft 29. The shaft 24 carries the pulleys 30 and the 25 shaft 29 the pulleys 31, over which endless traction belts B are trained. These belts are of the cross sectional configuration shown in Figures 2, 6 and 7, for instance, in order to permit them to conform to the internal shape 30 of the average cylindrical conduit. The reference character 32 designates longitudinal belt guards which prevent displacement of the belts and ride in contact with the surface of the conduit. The reference character 33 35 designates an apertured lug with which the wire (not shown) is connected. In addition I provide roller brackets 34 of the design seen in Figure 8. These brackets are mounted on the body 27 within a suitably shaped 40 recess and are provided with anti-friction rollers 35 which are shaped as seen in Figure 6 and which bear against the upper or crown portion of the conduit. The resilient action serves to press the tension belt firmly down 45 against the bottom of the conduit to insure effective traction.

50 In considering Figure 9 it will be observed that the only distinction here is that the traction belts 36 are of a flat surface configuration for use in conduits with square cross section and like wise the guards 37 vary in shape to correspond thereto.

55 It is therefore seen that it is within the scope of the invention to have the configuration of the device vary according to the particular shape of the conduit which it is to be used.

60 From the foregoing description and drawings it will be seen that I have developed an unusually animated creature like tractor which is started at one end of the conduit with wires attached thereto and which is self acting in carrying the wires through to the opposite end. This self acting and self 65 guiding tractor is well adapted for fulfilling

the requirement of a structure of this class. It is thought persons familiar with wire pulling and manual rodding will appreciate the practicability and advantages and features accompanying a machine of this kind. 70 Therefore a more lengthy description is regarded unnecessary.

75 Minor changes in size, shape and rearrangement of details coming within the field of invention claimed may be resorted to in actual practice if desired.

Having thus described the invention, what I claim as new and desire to secure by Letters Patent is:

80 A conduit tractor comprising an elongated body having a forwardly disposed portion of circular cross section and a rearwardly disposed portion of T-shaped cross section, said T-shaped portion being of relatively smaller cross section than the forwardly disposed portion, endless traction belts on opposite sides of the said rearwardly disposed portion and extending for the full length of said rearwardly disposed portion, a motor in the said forwardly disposed portion, a driving connection between the said motor and the said traction belts, and belt guards on opposite sides of the said rearwardly disposed T-shaped portion of the body and forming continuations of the head of the T, said belt 85 guards and traction belts having outer arcuate surfaces in conformity with the circular cross section of the said forwardly disposed portion of the tractor.

90 In testimony whereof I affix my signature.

100 JAMES R. JORDAN.
